UNITED STATES PATENT OFFICE.

GEORGE H. FORSYTH, OF HARVEY, ILLINOIS.

FORMING AND TEMPERING DISK WHEELS.

Application filed January 12, 1920. Serial No. 350,884.

To all whom it may concern:

Be it known that I, GEORGE H. FORSYTH, a citizen of the United States, residing at Harvey, in the county of Cook and State of Illinois, have invented certain new and useful Improvements in Forming and Tempering Disk Wheels.

The invention has for its object the possible simultaneous or concurrent forming and tempering of sheet metal bodies such as steel disk wheels whereby may be produced from a steel sheet a formed wheel body of uniform texture and temper and possessing in the highest degree qualities of spring resistance to deforming strains.

Disk wheels usually have been formed of low grade soft steel capable of being shaped in a die without rupture of the material into cupped or curved or wave-like section with out temper, or they have been tempered after forming and removal from the dies with resultant proportionately great loss from warping in the tempering process.

It has been considered from a manufacturing standpoint impracticable to form cup-like or transversely waved disks from previously tempered sheets, as also to temper such disks after forming; wherefore it has been usual to employ high grade spring steel in the manufacture of flat disk wheels only, and to make cup-like or transversely waved or cup disks of low grade steel.

By my invention I am able to produce wheel disks of any desired cross-section possessing spring temper while preserving unimpaired contour of the forming die due to the employment by me of high grade steel in a workable condition, readily adaptable to shaping in a die, and tempering and forming the same concurrently or while held in situ in the forming die.

For carrying out this forming tempering process and preserving the shape of the formation I have devised a die which I find adapted to the purpose although it is obvious that the process may be carried out by means mechanically devised differing structurally from those illustrated in the accompanying drawings.

In the drawings Figs. 1 and 2 are central vertical sections through the punch and matrix of a die, and taken respectively at an angle of 90° one to the other.

Having reference to the drawings, the bed 55 of the die is represented at 11, the matrix

at 12 and the punch at 13. The matrix is removable from its bed, the outer walls 14 of the matrix tapering slightly downward and the inner walls of the bed at 15 likewise tapering in order to guide the matrix into centered position in the bed. The matrix is hollow having an inner chamber 16 adapted to be flooded with water or other suitable cooling tempering fluid through the port 17 leading from the supply pipe 18. The matrix is also supplied with a cooling fluid above its face 19, through the port 20 and made to escape as occasion requires through the vents 21 in the lowest portion of the face to the hollow interior of the matrix. An outflow port 22 is provided from the interior of the matrix to an overflow channel 23 formed in the bed 11. A waste opening 24 leads from the face of the matrix adjacent its highest portion whereby the level of the liquid, hereinafter referred to as water, is normally maintained at the matrix of the die at the horizontal level indicated at 25. Radial grooves 26, shown in dotted lines, permit wide diffusion and an emergency escape of the liquid above and beneath the sheet being formed.

The punch 13 is provided with an inner cavity 27 supplied with a cooling fluid such as water through the port 28 from the flexible supply pipe 29 and out-flow is permitted through the port 30 connected with the flexible pipe 31. At the slotted portion of the lower face of the punch are openings 32 leading from the inner cavity of the punch to the lower face thereof and controlled by check valves 33.

Within the side walls 14 of the matrix are provided sockets 34 to receive stems 35 to project downwardly from the punch. Each of the stems is provided with a notch 36 adapted to be engaged by the detent 37 mounted in the wall 14 of the matrix and adapted to move laterally into sockets 34 under the influence of a spring 38 and to be withdrawn therefrom by the arm 39 of a bell-crank or other mechanical device under the control of the operator or press operating mechanism for a purpose more fully referred to hereinafter.

A sheet of steel, indicated at 40 is disposed above the matrix and below the punch. At this time the chambers within the punch and matrix are full of liquid and the liquid stands upon the face of the matrix at sub-

stantially the level indicated. Usually the sheet would have been previously heated as affording a sharper shaping of the metal, and may have undergone one or more successive steps approaching the final shape. In the final forming operation, as the punch 13 descends, the sheet 40, flat or preliminarily shaped, is forced into the matrix until near the end of the final forming stroke or 10 "kick" of the press, the lower face of the sheet comes in contact with the water within the matrix. Substantially at the same instant water is admitted from the interior of the punch to the outer surface of the sheet 15 by the actuation of the check valves 33. These valves do not sooner operate for the reason that the lower edge of the valve does not extend below the horizontal plane of the lowest portion of the punch and so long as 20 that portion of the sheet immediately below the check valve is not bent upwardly so as to press against the valve stem, the valve is not actuated thereby, but with the bending of the sheet into the concave lower face of the 25 punch the check valves are opened and the upper face of the sheet flooded with water.

It will be observed that the completion of the sheet forming operation and the application of the cooling fluid thereto are practically simultaneous.

When the punch reaches the limit of its forming stroke, the detents 37 snap into the notches 36, locking together the punch and matrix of the die upon the formed sheet absolutely preventing any warping of the body while it is being cooled. As the punch rises the matrix is lifted therewith and with the next or a subsequent downward stroke of the punch the matrix is again deposited in its bed, whereupon any appropriate mechanical connection between the detents 37 and the press operating mechanism is caused to withdraw the detents 37 releasing the stems 35 and permitting the punch to rise free of the matrix.

The sheet having been finally formed and tempered concurrently and while held against warping may now be removed from the matrix and another flat or partially shaped sheet disposed in the matrix or upon the punch. Obviously, the detents 37 may be locked out of operation by any catch device so that the matrix will not be coupled to the punch where it is found unnecessary to hold the formed sheet after its shape has been imparted thereto.

The same process may be carried out by preliminarily forming the disk while hot in a single or successive stages without tempering; then re-heating without regard to expansion or slight deformation; then again subjecting the disk to final shaping action in the die with concurrent tempering, either with water directly applied near the close of 65 the stroke as previously outlined, or the hol-

low die members may be flooded with water under pressure while clamped together on the work, and the water thus applied over the surfaces of the confined work through apertures in the faces of the punch and matrix. In any case the tempering is done concurrently with the final forming of the work in the dies.

I claim:

1. The method of shaping sheet metal bodies which consists in forming the sheet in a die and concurrently with the final stage of forming applying a tempering fluid thereto. 75

2. The method of shaping sheet metal bodies which consists in forming the sheet in a die and concurrently with the final stage of forming applying a tempering fluid and maintaining the formed body clamped within the die during the cooling thereof. 80

3. The method of shaping sheet metal bodies which consists in forming the sheet in a die and concurrently with the forming of the body applying a tempering fluid to the two faces thereof. 85

4. The method of shaping sheet metal bodies which consists in forming the sheet in a die and concurrently with the forming of the body applying a tempering fluid to the two faces thereof and maintaining the formed body clamped within the die during the cooling thereof. 90

5. An apparatus for concurrently forming and tempering sheet metal bodies, comprising a punch, a matrix, and means to apply tempering liquid to the sheet at the final stage of forming. 100

6. An apparatus for concurrently forming and tempering sheet metal bodies, comprising a punch, a matrix, and means acting automatically as the punch nears the end of its forming stroke to apply tempering liquid to the sheet at the final stage of forming. 105

7. An apparatus for concurrently forming and tempering sheet metal bodies comprising a hollow punch and a hollow matrix, means for applying a cooling liquid to the interior of each, means acting automatically as the punch nears the end of its forming stroke to admit the liquid from the punch interior to one side of the sheet being formed and for concurrently applying cooling liquid to the other side of the sheet. 110

8. An apparatus for concurrently forming and tempering sheet metal bodies comprising a hollow punch, a hollow matrix, means for applying a cooling liquid to the interior of each, means to permit the escape of the liquid, check valves acting automatically as the punch nears the end of its forming stroke to admit the liquid from the punch interior to one side of the sheet being formed and means to maintain a body of liquid within the face of the matrix for application 125 120 125 130

to one side of the sheet concurrently with the application of the liquid to the other side of the sheet.

9. An apparatus for concurrently forming and tempering sheet metal bodies comprising a punch, a matrix, means to apply tempering liquid to the sheet in its final form, means to couple together the punch and matrix to clamp the formed sheet therebetween for cooling during the return of the punch and to uncouple the two and release the formed sheet at a subsequent stroke.

10. An apparatus for concurrently forming and tempering sheet metal bodies comprising a punch, a matrix, means acting automatically as the punch nears the end of its forming stroke to apply tempering liquid to the sheet in its final form, means to couple together the punch and matrix to clamp the formed sheet therebetween for cooling dur-

ing the return to the punch and to uncouple the two and release the formed sheet at a subsequent stroke.

11. An apparatus for concurrently forming and tempering sheet metal bodies comprising a punch, a matrix, means to effect the cooling of the sheet in its final form, means to couple together the punch and matrix to clamp the formed sheet therebetween for cooling during the return of the punch and to uncouple the two and release the formed sheet at a subsequent stroke.

In testimony whereof, I have hereunto signed my name in the presence of two subscribing witnesses.

GEORGE H. FORSYTH.
